(57) **CLAIM**

The ornamental design of a hand tool illustrated, substantially as shown and described.

DESCRIPTION

FIG. 1 is a perspective view of a hand tool embodying the design of the present invention;

FIG. 2 is a bottom plan view of the hand tool illustrated in FIG. 1;

FIG. 3 is an end view of the hand tool illustrated in FIG. 1;

FIG. 4 is an end view of the hand tool illustrated in FIG. 1;

FIG. 5 is an opposite end view of the hand tool illustrated in FIG. 4, the left side view being a mirror image of the right side view;

FIG. 6 is a right side view of the hand tool illustrated in FIG. 1; and,

FIG. 7 is a left side view of the hand tool illustrated in FIG. 1.
